UNITED STATES PATENT OFFICE.

ISAAC A. BAUM, OF CHICAGO, ILLINOIS.

FRAME CONSTRUCTION.

Application filed July 5, 1927. Serial No. 203,384.

The subject matter of this application was first disclosed in my application Serial No. 23,626, filed April 16, 1925, Patent No. 1,578,796 of March 30, 1926.

According to common practice, two studs are employed to frame an opening, of the two studs, the outer, or one nearest the window box, is called a cripple stud, because it is terminated at the point of the lower extremity of the opening. My invention relates to a new arrangement of the studs, whereby a saving of wall thickness is effected.

In a frame building, when the studs are set, the sheathing is nailed thereto in the usual manner, the ends of the sheathing boards terminating short of or flush with the face of the stud. Thereafter the cripple studs are set and are positioned so that their side faces are flush or in a plane with the exterior surface of the sheathing. Thereafter, the blind stops are nailed to the cripple studs and the necessary furring strips applied on the exterior wall surface. This results in a construction in which one side edge of the stud is flush with the outer surface of one blind stop, and the outer surface of the furring strip is flush with the outer surface of the other blind stop. This results in a saving according to the thickness of the sheathing employed and facilitates construction in other respects, especially where plaster terminals of the form illustrated in the drawing are used. It provides the required dead air space between the outer wall covering and the sheathing and permits of an adaptable wall construction in which there is a substantial saving in thickness.

The invention will be more readily understood by reference to the accompanying drawings, in which;

Fig. 1 is an elevation of a wall having a window opening, and

Fig. 2 is an enlarged sectional view on the line 2—2 of Fig. 1.

In the drawings, and referring particularly to Fig. 2 it will be seen that I provide a stud, 10 to which sheathing 11 is nailed in the usual manner, the ends of the sheathing extending no farther than the face of the stud. After this much of the construction has been completed, the settling of the building having progressed substantially, the cripple studs, 12 are set. These cripple studs are staggered relative to the studs 10, being positioned so that one edge 13 is flush with the

outer surface 14 of the sheathing. Blind stops 15, 16 are then nailed to the cripple stud. The window box is completed by the stile 17. Thereafter, lath, indicated at 18, 19 is applied to the outer and inner walls respectively, the lath on the outer wall being applied in a plane with the outer surface of the dead stop, 15. This leaves dead air space 20 between the sheathing and the plaster 21, which is later applied to the lath. On the inner wall surface the lath is applied in a plane with the outer surface of the dead stop 16 and the stud 10 which are flush, and plaster 22 is likewise applied to the lath. The means for providing the dead air space 20 may include furring strips 28 or similar devices.

Preferably in this form of construction, I utilize a metal plaster terminal having a base 23, a right angular portion 24 and a backwardly bent flange 25; the base portions 23 are secured to the dead stops at the proper point, the terminal member serving as a plaster ground. Thereafter, the opening may be finished by suitable molding such as indicated at 26 and 27, this being selected according to the architect's design. In either case, the molding may be projected into the plane of the plaster terminal and serve as a support therefor as well as a means for developing the required shadows and lines. The construction adapts itself to many different forms of construction so far as the plaster terminal is concerned, although this invention is directed more particularly to the staggered stud arrangement.

The device is capable of considerable modification, and I do not wish to be limited except as indicated in the appended claims.

I claim:

1. In a wall having an opening, the combination of a stud, sheathing secured thereto, a cripple stud arranged in staggered relation to the stud with one face flush with the exterior face of the sheathing, and blind stops secured to the opposite outer faces of the cripple stud.
2. In frame construction, the combination of a stud at each side of an opening, a cripple stud, set alongside of each stud, said cripple stud being staggered relative to said studs, sheathing secured to the studs, the outer surface of the sheathing and the cripple studs being substantially flush, and blind stops secured to the cripple studs.

3. In combination, in a frame building, studs at an opening, sheathing secured to the studs, cripple studs arranged in off-set relation relative to the studs with the outer surface of the cripple stud flush with the outer 5 face of the outer surface of the sheathing, lath applied to the inner wall surfaces flush with the inner sur-

face of the stud, lath applied to the outer wall surface, and means spacing said outer lath away from said sheathing.

10

In testimony whereof I have affixed my signature.

ISAAC A. BAUM.
